UNITED STATES PATENT OFFICE

LAURENCE M. PERSONS, OF ST. LOUIS, MISSOURI, ASSIGNOR TO EMERSON ELECTRIC MANUFACTURING CO., OF ST. LOUIS, MISSOURI, A CORPORATION OF MISSOURI

FAN

Application filed August 4, 1930. Serial No. 472,848.

My invention relates to an improvement in fans and has for one object the provision of a fan which will deliver air generally laterally in all directions. Another object is the provision of a fan adapted to deflect the air from a vertical to a horizontal direction of movement. Another object is the provision of a fan of the above type adapted to deliver a breeze simultaneously in a plurality of directions. Another object is the prevention of torsional vibration in the fan and the production of quiet operation. Another object is the provision of a fan adapted to be combined with a lamp whereby a single installation for example on a desk or table, may serve the double function of illumination and of draft or air current production. Other objects will appear from time to time in the course of the specification and claims.

20 I illustrate my invention more or less diagrammatically in the accompanying drawings, wherein—

Figure 1 is a vertical section;

Figure 2 is a section on the line 2—2 of Figure 1; and

Figure 3 is a section on the line 3—3 of Figure 1.

Like parts are indicated by like symbols throughout the specification and drawings.

30 Referring to the drawings, A generally indicates a lamp base, which may include the stem A¹ and the supporting foot A².

Mounted within the lamp shell A is a motor housing structure which may include the 35 outer housing or shell B which carries the field coils B¹. B² indicates a bearing sleeve and B³ a cover or closure for the shell B. The structure so formed is supported within the shell A, for example, by the bolts or 40 screws B⁴, the heads B⁵ of which abut against countersunk preferably yielding or anti-vibrational bushings or washers B⁶. The inner ends of the upper screws B⁴ pass through apertures in a ring B⁷ associated with 45 the cover plate B³. The motor structure is thereby centered in and supported in the shell A, and rattle or vibration is prevented by the yielding washers.

Projecting upwardly through the motor 50 structure is the fixed shaft C the lower end

of which is fixedly supported in any suitable fashion in the bottom of the hub or sleeve B². Fixed in relation to the upper end of the shaft C is the sleeve C¹, which may be locked in relation to the shaft C, as by the set screws 55 C². Associated with the upper portion of the sleeve C¹ is a gear reduction housing C³, which also serves to support a combined cover and electric light support C⁴ herein shown as in the form of a concave disc, which may 60 support any suitable number of light sources, for example incandescent bulbs C⁵. The wiring therefor is not herein indicated; but it will be understood that they may be connected in any suitable manner, for example, with 65 a source of commercial electric power. C⁶ is in effect an upward or interrupted continuation of the fixed shaft C and, like it, is fixed against normal movement in relation to the sleeve C¹. It supports at its upper end a 70 sleeve C⁷ to which is secured a concave cover member C⁸.

Surrounding the above described structure is a frame work herein shown as a truncated cone which includes the upright rods D, the 75 upper circumferential circular rod D¹ and the lower circumferential circular rod D². The lower rod D² is supported by the radial rods D³, the inner ends of which are secured as by the screws D⁴ to the exterior upper edge 80 of the lamp base A. D⁵ are any suitable circumferential reinforcing rods or guard members.

Mounted upon the above described wire or 85 rod frame work are a plurality of air deflecting vanes E, herein shown as circumferential rings the inner portion of which inclines downwardly and inwardly, the outer edge of which inclines somewhat downwardly and outwardly. In practice these vanes are 90 curved or set at any desired arc or angle, in order to deflect an upward flow of air through the lamp body and to direct it outwardly and more or less downwardly. The contour of the individual vanes may of course be varied 95 widely, depending upon the use to which the device is to be put and the desired angle or direction of delivery of the flow of air.

Mounted for rotation about the shaft C is 100 the fan hub G. Mounted on the hub are the

inclined fan blades G^1 , which are preferably so inclined, in relation to the direction of rotation of the fan, as to direct an upward circulation of air through the device. The fan is concealed, laterally, by the deflector E^1 , which extends downwardly from the outer edge of the lowest of the vanes E and is herein shown as curled about the circumferential rod or support D^2 . The lower portion of the hub G is herein shown as attached to the armature sleeve or bearing G^2 , associated with which is the rotating armature G^3 of the earlier described motor. The sleeve is shown as resting on the ball bearing structure G^4 within the motor sleeve B^2 . The upper end of the sleeve G is laterally expanded to form a pulley or driving member G^5 , about which passes a belt G^6 which in turn drives a pulley G^7 mounted against rotation in relation with the shaft G^8 . The shaft G^8 rotates in a sleeve G^9 which forms part of or is associated with the earlier described sleeve C^1 . At its upper end said shaft carries the worm G^{10} in mesh with a gear G^{11} , which in turn rotates a worm G^{12} in mesh with a gear G^{13} . The gear G^{13} serves to rotate the sleeve G^{14} ; which has associated with it the laterally extending supporting disc G^{15} upon which are mounted rotating baffles G^{16} , the lower edges of which are spaced and supported by the circumferential wire or support G^{17} .

It will be realized that whereas I have described and shown a practical and operative device, nevertheless many changes might be made in the size, shape, number and disposition of parts without departing from the spirit of my invention. I therefore wish my description and drawings to be taken in a broad sense diagrammatic and illustrative rather than as limiting me to my specific showing.

The use and operation of my invention are as follows:

I provide an improved form of combined lamp and fan in which a fan is concealed and housed and protected. The appearance of the usual type of desk fan has long been recognized as objectionable; and it is also an annoyance if only adding to the clutter of material upon the desk of a busy man. My combined lamp and fan reduces the number of articles needed in obtaining both illumination and air circulation. Among its positive advantages are the elimination of the necessity of having a fan in addition to a lamp, the concealment of the unsightly fan, and the protection of the fan from damage and the protection of the hand of the operator. I have diagrammatically shown a protecting and reinforcing structure including the rods D^3 and D^6 . It will be understood that these parts are preferably so spaced and proportioned as to make it difficult or impossible for the operator involuntarily to insert a finger within the fan structure. Thus the fan is far safer to

use than the ordinary conventional fan with exposed blades or with blades inefficiently housed in more or less open metal screen.

The vanes E serve as a shade for the lamp, it being if desired so proportioned as to prevent the escape therethrough of any substantial amount of light from the bulbs C^5 . Rotation of the motor, and thus of the fan G^1 , draws air upwardly into the lamp shade area. This air is constrained to pass outwardly between the vanes E . These vanes are so formed as to convert the upward movement of the air into a lateral movement. In the form of vane shown in Figure 1 herein, the air delivery will be somewhat downwardly toward the table top, and the table top itself serves as an additional deflector or spreader of the air circulation.

In order to increase the penetration of the air current, I may provide the rotating baffles or shutters G^{16} which revolve on the inside of the shade, allowing the breeze to be thrown, in the form herein shown, only in two opposite directions.

The spoke mounting of the motor upon the screws or spokes B^4 eliminates the torsional vibration from the shell and base of the lamp and produces quiet operation.

I claim:

1. In a combined lamp and fan, a base, a motor associated with said base, an air-pervious lamp shade, a fan, associated with said motor, adapted to direct a current of air laterally outwardly through said shade, and illuminating means positioned within said shade.

2. In a combined lamp and fan, a base, a motor associated with said base, an air-pervious lamp shade, a fan, associated with said motor, adapted to direct a current of air laterally outwardly through said shade, illuminating means positioned within said shade, said shade including a plurality of air directing vanes.

3. In a combined lamp and fan, a base, a motor associated with said base, an air-pervious lamp shade, a fan, associated with said motor, adapted to direct a current of air laterally outwardly through said shade, illuminating means positioned within said shade, and means for directing air outwardly through said shade in one or more restricted currents.

4. In a fan, a base, a motor positioned within said base, a fan associated with said motor, and mounted for rotation about a generally vertical axis, said fan being adapted to draw air upwardly, and a plurality of circumferential vanes positioned above said fan and about the air column delivered by the fan, said vanes being adapted laterally to direct the air upwardly drawn by the fan.

5. In a fan, a base, a motor positioned within said base, a fan associated with said motor, and mounted for rotation about a

generally vertical axis, said fan being adapted to draw air upwardly, and a plurality of circumferential vanes positioned above said fan and about the air column delivered by the fan, said vanes being adapted laterally to direct the air upwardly drawn by the fan, and a light source supported upon said base, said vanes being arranged to form a lamp shade therefor.

5 6. In a fan, a base, a motor positioned within said base, a fan associated with said motor, and mounted for rotation about a generally vertical axis, said fan being adapted to draw air upwardly, and a plurality of vanes positioned above said fan, said vanes being adapted laterally to direct the air upwardly drawn by the fan, and a rotary shutter associated with said vanes, and means for rotating it.

10 7. In a fan, a base, a motor positioned within said base, a fan associated with said motor, and mounted for rotation about a generally vertical axis, said fan being adapted to draw air upwardly, a light source supported upon said base, and a shade therefor, said shade including a plurality of circumferential vanes, adapted to propel air outwardly through said shade, said vanes being adapted to prevent direct lateral illumination.

15 8. In a fan, a base, a motor positioned within said base, a fan associated with said motor, and mounted for rotation about a generally vertical axis, said fan being adapted to draw air upwardly, a light source supported upon said base, and a shade therefor, said shade including a plurality of vanes, adapted to propel air outwardly through said shade, said vanes being adapted to prevent direct lateral illumination, and a rotary shutter positioned within said vanes, and a driving connection interposed between said shutter and the motor.

20 Signed at St. Louis, State of Missouri, this 21st day of July, 1930.

25 LAURENCE M. PERSONS.
